(57) **CLAIM**

I claim the ornamental design for an inner tube of reaction tube for semiconductor manufacturing equipment, as shown and described.

DESCRIPTION

FIG. 1 is a front, top and right side perspective view of an inner tube of reaction tube for semiconductor manufacturing equipment showing my new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof; and,

FIG. 8 is a cross-sectional view taken along line 8-8 in FIG. 2.

The dash-dot broken lines in the drawings illustrate the boundary of the claim and form no part of the claimed design.

The dash-dash broken lines in the drawings illustrate portions of the article that form no part of the claimed design.
